METHOD AND APPARATUS FOR IMPACTING A STREAM AT HIGH VELOCITY AGAINST A SURFACE TO BE TREATED

James A. Browning, Hanover, N.H., assignor to G. H. Tennant Company, Minneapolis, Minn., a corporation of Minnesota

Filed Apr. 21, 1958, Ser. No. 729,725
15 Claims. (Cl. 51—8)

This invention, a continuation-in-part of my pending application, Serial Number 557,100, filed January 3, 1956, relates to the treatment of metals and other materials by such techniques as sandblasting, steam cleaning and impregnation. The principles of this invention are particularly applicable to the removal of deposits such as rust, grease, paint and dirt and to the impregnation of surfaces with protective coatings of paint and similar substances.

Sandblasting is a common and extremely effective technique for the removal of undesirable deposits from the surfaces of structures, machines, ships, castings and the like. The common sandblasting system uses a stream of high velocity air to propel the sand or other abrasive against the work to be cleaned. The usual source for such a high velocity stream of air is the expansion of compressed air from high pressure through a nozzle to atmospheric pressure. The abrasive or other material is introduced into the air stream at a point ahead of the nozzle. The abrasive is given high velocity as it is entrained into the air stream. When an abrasive exhibiting sharp edges and corners is employed, its action upon striking the material is both of a cutting and impact nature. When cutting action is not desired, round metal shot is substituted for the sharp abrasive.

The effectiveness of the blasting operation is directly proportional to the velocity at which the material strikes the work and to the mass of material delivered at that velocity. This is due to the higher kinetic energy contained in each particle at the higher velocity. The more particles contained in the stream, the more impacts per unit time.

It is current practice to use an air compressor for such blasting purposes whose capacity is well above the air requirements of the specific blasting machine being used. Such a recommendation is due to the desire to keep the air pressure before expansion at a sufficiently high level to insure sonic exit velocity from the nozzle. A reduction of the inlet air pressure leads to a reduced air jet velocity with subsequent reduction in cleaning effectiveness.

Steam cleaning is the process in which steam is projected at the surface to be cleaned. The state of the steam may be represented by a mixture of hot vapor in equilibrium with its liquid phase, or superheated. The state is determined by the amount of heat contained in a unit mass of the water. Current types of steam cleaning equipment make use of various cleaning agents such as detergents. Such detergents are effective in removing oil, grease, dirt and similar deposits. However, steam cleaning as it is presently practiced, is not effective in removing rust and other tenacious deposits.

In most steam cleaning applications the effectiveness of the cleaning operation is proportional to the temperature of the steam or steam-water mixture. Thus, it is desirable in many cases to use the steam at high temperature. However, detergent action may be adversely effected if the temperature is too high. It is important that proper control over the quantity and temperature of the mixture flowing be maintained.

The present invention is an internal burner device which make use of the combustion of an oxidant and a fuel to effect the attainment of high energy levels. Air is first introduced into an internal combustor where its oxygen

2

combined with fuel in a combustion process carried out at very elevated pressure. Due to the combustion reaction, the energy level of this air is raised approximately eight-fold above that of compressed air expanded through the same pressure differential with no heat addition. Such an energy increase represents a velocity increase of about 2½ times. Readily flowable material, such as sand, other particulate matter, and/or liquid, is introduced into the hot products of combustion. The higher velocities attained in such a system are very beneficial in many applications. This invention is of great economic importance, as the eightfold increase in the energy is obtained by a relatively small addition of inexpensive fuel.

In the steam cleaning application the oxidant and fuel are burned at elevated pressure in an internal combustor. Water is added to the products of combustion. Heat is extracted from these hot products turning a portion, or all of the water into steam. The combined steam and products of combustion form a mixture which exhausts at high velocity from the chamber through the nozzle. A very effective cleaning jet is thus formed. The present invention when used for steam cleaning, clearly exhibits the value of the additional kinetic energy contained in the jet. Conventional steam cleaners have low jet velocities and are not nearly so effective in the removal of thick deposits.

The impregnation of surfaces for protection from corrosive action requires that the impregnating material completely coat the surface. For example, high velocity projection of paint particles is known to result in the deeper penetration of the paint into surface imperfections than when brushed on. Such penetration leads to better bonding between the surface and the paint film.

When a particle in plastic condition impinges on a surface at high velocity the particle spreads out radially to an extent determined by its size and velocity at impact. Such later spreading is conducive to good bond strength between adjacent particles when subsequently solidified. Mechanical bonding is proportional to the impact velocity.

40 Particle size also effects the tendency of particles in both the liquid and plastic state to deform on impact. The smaller the particle, the more difficult such deformation becomes. This is due to the increase of surface tension with diminishing radius. The extremely high velocities of my internal burner jet assures the desired high particle velocity.

An additional advantage of the internal burner as a propelling device lies in the heat content of the jet. Such liquid materials as lacquers and plastics, which 50 after application solidify, are commonly heated prior to spraying. This heating is accomplished batchwise or in continuous fashion by heating the liquid prior to introduction into the propelling medium. The temperature to which this material may be heated when in spray 55 form, is limited by the temperature of the relatively cool propellant air. Although the liquid may have sufficient heat content before spraying, much of this heat is excreted by the propelling gases.

In some cases a thinner must be added to provide 60 proper viscosity values. The ratio of thinner to paint may be greatly reduced when elevated spraying temperatures are used. This allows for the deposition of thicker dry films. Solvents not required for flowout disappear between the spray gun and target. By allowing the 65 material to be deposited to remain at a relatively low temperature prior to its introduction into the thermal jet, the material can be brought to its most desirable temperature within a matter of a few milliseconds. A comparable period of time is required to deposit the 70 material. In this manner, it is possible to decrease the time for the drying or setting of such materials. This fact, plus the high velocities imparted, makes the internal

burner a valuable addition to the plastic and paint spraying fields.

It is apparent that the internal burner is well suited to impart both kinetic and thermal energy to particles introduced into its jets. Such particles may be composed of solids, liquids, and plastics as well as suspensions of solid particles in a liquid medium—a slurry.

The definition of "particles" as herein used refers to any readily flowable material introduced into a gaseous jet for the purpose of raising the kinetic and/or thermal energy level of the added material. The material may be in a form other than particulate when introduced, and in such case it is transformed by thermal and shearing means into such particles.

To lower the jet temperature of a suspension of particles contained in the products of combustion of an internal burner it may be necessary to add diluent air, or liquid, to the jet. For example, such a diluent may be added to the jet prior to the introduction of the material to be sprayed. Such a system is applicable to the spraying of paint by means of a jet composed of the products of combustion of a flame and a substantial proportion of superheated steam.

The structure, functions and advantages of my internal burners will be more apparent from the following description made in connection with the accompanying drawings, wherein:

FIG. 1 is a longitudinal sectional view of an embodiment of my internal burner;

FIG. 2 is a cross section taken on the line 2—2 of FIG. 1, showing the structure of the combustion chamber and the relationship between said chamber, the inner and outer tube, and the nozzle;

FIG. 3A is a cross sectional view taken on the line 3A—3A of FIG. 1, showing the injector piece;

FIG. 3B is a detail vertical section showing the arrangement of the fuel-inlet-system within the injector piece;

FIG. 3C is a detail section showing the air-atomization provided for breaking up a liquid fuel;

FIG. 4 is a rear elevation of the burner showing the injector piece;

FIG. 5A is a detail vertical section showing the use of an aspirating section for inducing water into the exiting jet;

FIG. 5B illustrates in vertical, longitudinal section a water-cooled nozzle employing pressure-fed water;

FIG. 6 is a longitudinal cross section of the rear portion of a burner system utilizing a principle of this invention for the axial injection of liquid through the combustion chamber;

FIG. 7 is a graph showing the results of tests conducted to determine the effectiveness of the burner when used for sandblasting as compared with conventional blasters;

FIG. 8 is a graph contrasting test results showing the effectiveness of slurry cleaning when using my internal burner against conventional slurry cleaning;

FIG. 9A is drawn to show a typical sand feeding system; and

FIG. 9B is a detail view of an orifice system for regulating the air flow propelling the sand to the burner unit.

The use of such internal burners for these purposes can better be understood by reference to the drawings. FIG. 1 is a longitudinal sectional view of the complete burner for use in blasting operations where an abrasive grit is introduced into the products of combustion. The air for combustion is also used to cool the hot walls of the burner and the nozzle 27. This air enters the burner from a hose (not shown) attached to the projection sleeve 13 by means of the threads 12. The air passes through the passage 29 into passage 70, shown in FIG. 3A. Still referring to FIG. 3A, the air is metered into

the passage 72 by the annular area contained between the valve seat 71 and the valve 75. The metered air then passes through the short circular passage 73 into the large annular supply-passage 16 at the rear of the burner, whence it is distributed forwardly to the elongated, narrow, annular passage 17 contained between the large outer tube 40 and the middle tube 42. The air travels to the front diminished end of the burner where it transfers through the circumferentially spaced ports 18 to a second, elongated, annular cooling passage 19 contained between the middle tube 42 and the nozzle 27. The air passes at high velocity over this nozzle providing the effective cooling required. The air next passes around the reducer section 25 which is of an annular, truncated conical form, into the annular region 24a contained exteriorly and around the combustion chamber 24. The high velocity air passing between a multiplicity of external, longitudinal fins 28 (see FIG. 2) cools the combustion chamber 24. The air is then distributed into the annular well 21 through a plurality of radial ports 20 at the rear of the burner and thence into the rear of the combustion chamber 22. In passing into the chamber 22 a recirculation of the air is realized due to the larger cross sectional area of the chamber 22 in comparison with the well 21. This recirculation, near the rear injector piece 10, helps stabilize the combustion reaction.

When liquid fuel such as number 2 fuel oil is used, thorough atomization is required for reliable ignition at low temperature. The use of a small flow of high pressure air is very effective in producing good fuel atomization. Referring to FIG. 3B, the fuel oil is first metered and enters the injector piece 10 through the threaded, circular passage 90. The fuel is conducted through the relatively small, forwardly extending passage 91 to a small injector port 92. Atomizing air passing at high velocity from the passage 61 (FIGURE 3C) intersects the fuel flow producing the desired fuel droplets of small size. The passage 60, which conducts the air to passage 61, connects with air passage 29 (see FIGS. 3A and 3B), which is on the high pressure side of the metering valve used to control the combustion air flow.

Combustion is initiated by a spark produced across the annular area 35 (see FIG. 1) contained between the electrode 31 and the plug body 33. A small amount of air enters the plug through the small radial ports 36 communicating with the upper portion of the annular cooling passage 19, to pass through the annular area 35 into the combustion chamber 22. This flow of air serves a dual purpose. It lengthens the arc path into the gases to be ignited and serves to cool the plug body 33 and the electrode 31. The plug body 33 is attached by means of threads to the spud 34 which is welded to the outer tube 40. The ceramic section 32 of the ignition plug provides electrical insulation between the electrode 31 and the plug body 33. The threads 37 are provided for the attachment of a shield lead housing (not shown). A conventional high voltage transformer (not shown) of 10,000-volt secondary voltage is used to provide the spark energy. This transformer may be located well away from the burner and does not have to be carried when the burner is being hand-held.

Combustion is essentially completed within the chamber 22. The products of combustion travel through the reducer section 25 into the nozzle 27 from which expansion to atmospheric pressure produces a high velocity jet.

The abrasive particles or other material are introduced through the rear axial passage 53 contained in the piece 50. For blasting purposes a small flow of air carries these particles through the hose length 114 (see FIG. 9A) which is connected by means of the threads 52 to the piece 50. This secondary flow of air is consumed in the combustion reaction along with the air used for cooling the burner. The abrasive becomes entrained in the

combustion gases. Momentum-transfer from the products of combustion accelerates these particles to much higher velocity than could be obtained using conventional blasting means.

The nozzle 27 is subject to the abrasive action of the particles passing through it. Wear is rapid, and in the case of cast alloys, the nozzle must be replaced frequently. Cast iron containing a high percentage of manganese has been found to be suitable nozzle material. Tungsten and boron carbide nozzles are not suitable for use with air cooling due to their oxidation at the elevated temperature of operation. Titanium carbide may be used.

The nozzle is detachably held in place between the reducer section 25 and the retainer ring 45, which has an externally threaded sleeve.

The piece 50 must project beyond the point of intersection of the air entering the well 21 (see FIG. 1) through the radial ports 20. In this fashion the recirculation of the primary combustion air is not deleteriously influenced by the secondary flow of air and its contained particles. For best operation, the annular face 54 of piece 50, should project slightly beyond the face of injector piece 10.

Any action which interferes with the stabilization process will extinguish the flame, thus obviating the use of such a system as a practical heat source. This adverse condition is particularly true when water is injected into a combustion chamber. Such water is able to extract a sufficient amount of heat from the reacting gases to reduce the heat output from these gases to below that necessary to keep the combustion going.

It is possible to avoid this problem of quenching of the flame reactions by injecting the water into the products of combustion at a point well removed from the injector end of the unit. Such a system is shown and described in my pending application, Serial No. 557,100, filed January 3, 1956.

The present invention allows for the embodiment of axial injection; thus, a longer path is provided for the injected material. This leads to longer residence time of the particles within the hot gases allowing more complete heat and momentum-transfer.

It has been found that the injection of water axially down the combustor leads to an extremely critical situation. If the water jet should break into droplets which disperse through the chamber 22 at a position not sufficiently far removed from the injector piece, the flame may be extinguished. It is possible to eliminate this initial break-up of the water jet by controlling the momentum of said jet. If the water flow is projected axially downstream in a stream of sufficient momentum, the break-up process does not occur until a position is reached well down the chamber length. FIG. 6 illustrates an internal burner as used for steam cleaning, or for other liquid injection into the hot gases. It has been found that the liquid injector tube 103 should extend well into the chamber 22. The liquid is first metered by a valve (not shown) and passes through a hose (not shown) threaded to tube 103 by means of the threads 104. The axial passage 105 conducts this liquid to the smaller injector port 106. The size of the port 106 is important with respect to producing a jet 107 which retains its identity until a point well down the combustor length is reached. At this point the jet suddenly breaks into droplets 108. The diameter of the injector port 106 together with the mass flow of the liquid determine the momentum contained in the jet 107.

When air expands into the atmosphere from a pressure at least double that of the atmosphere, it is possible for the resulting jet to reach sonic or higher velocity. Under perfect conditions, a nozzle which contracts to its final opening size, or for a tube, the resulting velocity is sonic. For a nozzle, which contracts to its minimum section and then expands, the jet velocity can reach higher than

sonic value provided the inlet pressure is sufficiently great. The sonic velocity of a gas at the gas temperature is

$$V_{\text{sonic}} = \sqrt{kgRT}$$

$$5 \quad k = \frac{c_p}{c_v}$$

g is the acceleration of gravity

R is the gas constant

T is the temperature.

10 It is thus seen that the sonic velocity for any one gas is a function of the absolute temperature alone. For an air jet at 65° F. the sonic velocity is 1125 feet per second. The static temperature of the products of combustion for an air-fuel internal burner is about 2800° F. This gives a sonic velocity of about 2500 feet per second. It is this increase in jet velocity which makes the internal burner so effective in increasing the efficiency of the sandblasting operation.

15 20 Although a delivery pressure double that of the atmosphere leads to sonic velocity of the jet, an additional pressure head must be provided to accelerate the particles to high velocity. It is for this reason that the compressor is required to deliver air at a pressure of at least 90 p.s.i.g. for maximum blasting effect.

25 FIG. 7 correlates results obtained from tests conducted on the use of internal burners for sandblasting operations. The ordinate represents the increased cleaning effectiveness of the higher particle velocities with respect to that for conventional compressed air blasting. The internal burner of this invention is thus compared with conventional blasting systems for a range of comparable air flows. The abscissa represents the particle velocity. The relative effectiveness represents the area cleaned using my burner system, divided by the area cleaned using compressed air with no heat addition. No attempt has been made to include the quality of the resulting cleaning, although in all cases the finish produced with the internal burner was superior to that by conventional means.

30 35 40 Particle velocity has been calculated assuming that the final velocities of the gaseous jet and entrained particles are the same. The combustor jet velocity with no particle entrainment attains a momentum value which is conserved. This momentum is distributed between the gaseous medium and the abrasive in relation to their relative mass flows to produce the particle velocity plotted.

45 50 55 The top curve of FIG. 7 (for nearly constant sand flow) shows the effect of particle velocity on cleaning effectiveness. A fourfold increase in the area cleaned per unit mass of abrasive results. Increase in particle velocity has a nearly linear effect on the cleaning effectiveness.

60 65 70 The lower curve of FIG. 7 represents the increase of effectiveness per unit of air consumption. The energy level of a flow of compressed air is increased approximately eightfold when the available oxygen contained in that air is burned. This added energy arises from the heat of combustion which is released to increase both the temperature level and the specific volume of the gas. The energy equation contains the velocity to the second power. The eightfold energy increase would thus be expected to increase the throat velocity of a cold air stream by about 2½ times.

75 80 85 The results obtained by test agree with the above theoretical discussion. Per unit of air flow, the cleaning effectiveness would be expected to be somewhat less than 2½ times.

90 It has been found that the cleaning of deposits too difficult for present steam cleaning methods may be accomplished with the internal burner if a small quantity of abrasive powder is suspended in the water. The use of such an abrasive suspension is not practical in the conventional type of steam generator due to the formation of deposits on the inside of the heat exchanger tube walls. Only small quantities of such powders as aluminum oxide, pumice, or even common cement are required. In some

cases, it may be desirable to mix the abrasive with a detergent to utilize the beneficial features of each.

The use of small amounts of abrasive powder in steam cleaning applications is differentiated from slurry cleaning in this invention. Slurry cleaning makes use of much larger quantities of abrasive suspended in the water. The cleaning action is dependent on abrasive action rather than steam, although in some cases the steam may play a part. In the former case the abrasive is added to increase the effectiveness of steam cleaning. In the latter case, the major role is played by the abrasive.

When the use of such suspensions is required, it is recommended that the water and abrasive be thoroughly mixed within a pressurized tank. The mixture is then fed to the burner under a pressure greater than that in the combustion chamber. It is desirable to feed this suspension longitudinally through the combustor from an injector such as 103 of FIG. 6, although injection beyond the combustor, but ahead of the nozzle exit, is also possible.

Feeding of such a mixture of liquid containing a suspended abrasive may be accomplished by the aspirating action of the high velocity exiting jet. Such an aspiration system is shown in FIG. 5A. The jet from the nozzle 26 issues into the region 99 causing a partial vacuum to form. Water, or a mixture of water and abrasive is drawn through a hose connected to the fitting 97 into the region 99 via the small distribution ports 98. To obtain higher particle velocities, the length of the cylindrical passage in piece 94 may be extended. The maximum velocity obtainable is considerably less than that obtained by pressure feeding ahead of the nozzle orifice 26.

For most steam cleaning applications it is quite suitable to use the aspiration technique for drawing the liquid into the stream of hot gases. The water and detergent may be mixed and placed in an open container obviating the use of more complex pressure-feed systems.

The effectiveness of slurry cleaning is shown by the curves of FIG. 8, which compare the results of slurry cleaning using the burner of this invention with conventional slurry cleaning where no heat addition is used. Per unit of air flow, the cleaning effectiveness of the burner system, removing thick layers of enamel paint baked on metal, is approximately 11 to 1 when compared to the same air flow with no heat addition. The figures are heavily in favor of the burner system and it is thought that in this case the heat contained in the hot water plays an important part.

Sand blasting leads to the formation of large quantities of dust. Such dust can be a hazard to both personnel and equipment. It is desirable in many cases to introduce water into the exiting jet for the purpose of suppressing the formation of this dust. When using an air-cooled nozzle, the aspiration system shown in FIG. 5A and described for steam cleaning, may be used very effectively.

In many cases where water is to be used for such dust suppression, it is desirable to make additional use of the water for nozzle cooling. This allows the use of tungsten carbide nozzles which have an extremely long, useful life. FIG. 5B shows such a system. A burner adapted to water cooling of the nozzle requires different outer and middle tubes than in the case of the air-cooled burner. The outer tube is fitted with an internal ring 131a to contain the water from the cooling air. It is desirable to use air cooling for the combustion chamber as an elevated combustor wall temperature leads to better combustion efficiencies. The air passes through the annular passage 132 contained between the tubes 131 and 130 to a joint just ahead of the O-ring location. The air then passes through the combustor fins as before. Water is either drawn by aspiration action or supplied under pressure through the fixture 138 into the annular volume 139 contained between the nozzle and the forward, diminished end of tube 131. The nozzle is kept quite cool by the water passing

over its outer surface. The water, for the case shown, is forced under pressure through the circumferentially spaced, forwardly and inwardly extending ports 142 contained in the retainer ring 141 into the exiting jet. A retainer piece similar to induction piece of FIG. 5A is suitable for aspiration use coupled with nozzle cooling.

An additional advantage of the aspiration of water into the region containing the boundary of the exiting high velocity jet is its effect on reducing the noise level of that jet. For example, actual sound level measurements show a reduction of the sound intensity of 116 db without water injection to 96 db with water injection. Pressure feeding of the water ahead of the nozzle section does not reduce the noise level.

It is seen that the aspiration of water may serve several functions. First, it is useful for steam cleaning. Secondly, it provides a simple technique for dust suppression. Thirdly, the noise level of the jet is reduced to a much lower level.

20 In sandblasting, the use of water not only suppresses dust, but also takes an effective part in the cleaning action. The heat contained in the water has a softening effect on many deposits. For example, some paints are more easily removed when warmed. In some cases, it is desirable to add a stripper to help in the paint removal. 25 When live organisms are being removed by blasting, the effect of the hot water and steam are very desirable. An example of this is represented by the cleaning of barnacles from ship hulls. In many cases, they may be removed whole due to their less tenacious grip on the hull when subjected to high heat. Such deposits as Thiokol and other organic substances are more easily removed when first subjected to the heat contained in the hot water and steam.

30 It is possible with the sandblasting system shown to make use of the different features of the internal burner as best adapted to the job. For example, where thick encrustations of barnacles and other marine life are encountered, it may be desirable to stop the abrasive flow to use steam action alone to loosen the deposit. Such a step would then be followed by sandblasting. A time interval between the heating and blasting is desirable to insure maximum heat effect on the organisms. In other cases the steam and grit are combined.

35 Another desirable feature of the heat contained in the blaster jet is in the cutting of concrete containing an aggregate of high silica content. Concrete is quickly severed by the high velocity particles. The heat action tends to split the larger aggregate particles helping the cutting action.

40 FIG. 4 is a rear view of the injector piece 10. The small valve 93 meters the fuel. The larger valve meters the air for combustion. The valve knob 81 is directly connected to the valve stem 74. Referring to FIG. 3A, it is seen that the piece 79 guides the valve stem by means of the threads 82. The nut 76 holds the valve disc 75 to the stem 74. The O-ring 78 and the gasket 80 prevent the escape of the pressurized air to the atmosphere.

45 Gaseous fuels are more easily ignited than liquid fuels. The fuel injection system for such gases as propane and natural gas is shown in FIG. 6. The fuel is metered by a valve attached by means of the threads 101 to the injector piece 100. The fuel passes directly into one of the radial passages 20 to the wall 21.

50 To operate the internal burner using a liquid for the fuel, the unit being used for blasting purposes, the main air valve 116 (FIG. 9A) is turned on. Air passes into air hose 115 from the main air line 125. With the valve 81 closed, a small amount of atomizing air flows through the passages 60 and 61. With the ignition spark turned 55 on the fuel valve 113 is opened. The unit experiences ignition of the combustible mixture within the chamber 22. The air valve 81 is next turned to the desired value of air flow with the fuel flow adjusted to its corresponding best value. The spark system may then be turned off.

When the burner is adapted to sand blasting, it is necessary that a certain minimum flow of air be allowed to flow through the hose 114 and then through the passage 53 (see FIGS. 1 and 4), into the chamber 22. Without this flow of air, hot gases from the combustion region may enter the hose through the passage 53 resulting in overheating of the hose material. The same air flow is used to propel the sand or other abrasive through the hose 114. As soon as ignition is effected, the valve 119 is turned on. An orifice 124 (FIG. 9B) controls the air flow to the desired value.

The amount of air required to prevent heating of the hose 114 by the backflow of combustion gases and to propel the abrasive through the same hose, is small in relation to the amount of air which passes through the abrasive-feed hose of conventional blaster units. The particle velocity is thus reduced during passage through the feed hose 114. The extreme wear of the feed hose in conventional units is reduced considerably when the system of this invention is used. The major flow of air for the blasting process is represented by that air required for combustion which passes through the hose 115.

When the abrasive is pressure-fed to the burner unit, an arrangement as shown in FIG. 9A may be used. The tank 118 is first filled with the abrasive. With the abrasive feed valve 121 in the closed position, the tank 118 is pressurized with air by opening the air valve 126. To feed abrasive to the unit with valve 119 open, all that is necessary is to open valve 121 to a position which will deliver the desired abrasive flow.

A sketch of the burner with the necessary hoses and lines attached is shown in FIG. 9A. The burner 110 under full combustion intensity has a cool outer wall due to the flow of cooling air between the tubes 40 and 42 (see FIG. 1). To further reduce heat transfer from the combustion region to the outer tube, it has been found desirable to coat the combustor 24 (see FIG. 1) with a "flame-applied" coating of aluminum oxide 30. This coating, which ranges from 0.010 inch to 0.020 inch, by virtue of its low heat conductivity reduces the temperature of the combustor's outer circumference. The fins 28 (FIG. 2) offer maximum cooling of the combustor 24, reducing its temperature even further. A coating 43 (FIGS. 1 and 2) similar to that on the inner wall of the combustor further reduces heat flow. The outer surface of the tube 40 thus is maintained at a temperature which is not uncomfortable to the bare hand.

Spark ignition energy is supplied through the shielded lead cable 111 from a transformer located at a remote position. Successful ignition may be obtained with the transformer location being as far as 100 feet from the burner.

Fuel is supplied under pressure to the burner 110 through the hose 112. When propane is used, it is convenient to use the tank pressure of the fuel to act as the pressure source. When oil is used, a gear pump has been found to be quite satisfactory. During cold weather conditions the air-atomization system for the fuel oil is to be recommended. During warm weather, oil may be used satisfactorily with the injection system shown in FIG. 6. In this case the same injector piece 100 is suited for both liquid and gaseous fuels.

This invention supplies a simple and very inexpensive means for increasing the energy of a stream of compressed air. As shown, by the tests reported here, without any increase in air flow it is possible to obtain up to twelve times the cleaning effectiveness using a slurry, up to 3 times the effectiveness for abrasive blasting, and it provides a steam cleaning system which is much simpler than conventional units which require a large and expensive steam generator.

From the foregoing description, it will be apparent that I have conceived and provided a widely variable, new method of very substantially increasing the discharge

velocity of a stream which may consist in a number of readily flowable materials for use in impacting operations against a surface to be treated. The impacting operations may consist in sand or grit blasting with or without addition of steam or other detergent flowable material; or it may constitute steam cleaning operations with or without other detergents; or it may constitute impregnation, spreading and coating of pigment, bonding and other materials into and upon a surface to be treated.

My novel method, while embracing a number of selectively applicable and sequel steps, in its basic principle consists in producing a confined stream for subsequent impact discharge through the utilization and movement of combustible fluid media and introducing into such a confined stream, readily suspendable material and the step of igniting and reacting combustible fluid media to add thermal energy to the stream with the suspended material therein, whereby the discharge and impact velocity is very substantially increased.

In distinguishing from the prior art, my invention appears to be of such broad scope as to include the addition of thermal energy to a confined, moving stream whether combustion of fluid media is effected actually within the main moving stream or transmitted into said stream and also, whether the combustion is effected prior to the introduction of the suspendable material or after such introduction.

Within the scope of my method as described herein, the introduced, suspendable material may constitute solid particulate material, steam, chemicals, gaseous or liquid detergents, pigments, bonding and other surface-coating materials.

My method within its important ramifications, includes the introduction of the readily suspendable materials under the aspirating action of the main gaseous stream which is discharged from a duct of relatively small cross section into a larger duct.

In most instances (not necessarily), the combustion of an oxidant gas and fuel is effected prior to the introduction of the additional, readily flowable materials.

In use of my novel method for steam cleaning operations against a surface to be treated, water is introduced into the main gaseous stream composed of an oxidant gas and fluid fuel. The thermal energy obtained from the combustion of said oxidant gas and fuel prior to the discharge converts the water to steam (usually superheated steam). The water is preferably either injected into the chamber substantially axially of the flow of the combustible fluid media towards a restricted discharge and at high velocity or the water may be aspirated by the action of the gaseous stream after combustion, entering the flow near the ultimate area of discharge and in fact, after the main discharge of the products of combustion.

It will of course be understood that various apparatus and media for carrying out my novel multi-purpose methods may be employed, all within the scope of the broad, patentable aspects of the method invention.

It will further be understood that internal burner apparatus of the several basic structures disclosed herein, are particularly applicable for carrying out my methods and such structures and apparatus are quite closely linked with the essential method steps.

What is claimed is:

1. The method of impacting at high velocity, a stream against a surface to be treated, which consists in producing a confined and selectively continuous stream through movement of combustible fluid media, introducing into said confined stream, readily flowable, suspendable material of a class comprising hard particulate material, liquids, and suspension of solid particles in liquid media, combusting and reacting said fluid media in said movement to add thermal energy to said stream and said material suspended therein in travel, then continuously and directly discharging the ultimate stream produced against the surface to be treated, whereby the discharge

11

velocity thereof is very substantially increased as contrasted with said original continuous stream.

2. The method of producing and discharging a blasting stream against a surface, which consists in continuously moving a combustible fluid through a confined burner space, combusting said fluid in its movement within said space to materially increase the thermal energy and velocity of the resultant stream, introducing and suspending in such stream, readily flowable material, and without interruption of the travel of said stream, discharging the same against a surface to be treated.

3. The method of continuously producing and continuously discharging a blasting stream against a surface, which consists in continuously moving a combustible fluid through a confined burner space, combusting said fluid in its movement through said space to materially increase thermal energy and velocity of the resultant stream, continuously introducing and suspending in such stream, material of a class comprising hard particulate material, liquids and suspensions of solid particles in liquid medium, and without interruption of the travel of said stream, discharging the same against a surface.

4. The method set forth in claim 3 wherein aqueous moisture is introduced into said resultant stream.

5. The method set forth in claim 3 wherein water and hard particulate material is introduced into said resultant stream and suspended thereby.

6. The method of impacting a blasting stream against a surface which consists in continuously moving a fuel and also an oxidant into and through a confined burner duct, cooling the exterior of said duct by impingement of said oxidant thereagainst prior to introduction into said duct, combusting said fuel with the aid of said oxidant within said duct during movement of said oxidant and fuel to substantially increase thermal energy and velocity of the resultant stream, introducing and suspending in said resultant stream, readily flowable blasting material and without interruption of the travel of said stream, discharging the same against a surface to be treated.

7. The method of impacting at high velocity, a stream containing suspended material against a surface to be treated, which consists in producing a combustible stream at elevated pressure by continuously introducing and moving an oxidant gas and a fuel into a duct system having a discharge nozzle, combusting said oxidant gas and fuel prior to discharge and suspending readily flowable material in the resulting products of combustion and directly discharging the ultimate stream against the surface to be treated.

8. The steps set forth in claim 7 in which the oxidant gas is air and in which the combustion reaction takes place within said duct system at a pressure greater than 15 pounds per square inch gauge.

9. In apparatus for producing and impacting at high velocity, a stream against a surface to be treated, a medium defining a combustion chamber, a diminished discharge nozzle constantly communicating with the forward portion of said combustion chamber, means for continuously introducing a combustible fluid medium at elevated pressure into the rear portion of said combustion chamber, means for igniting said medium within said chamber and means for continuously introducing readily flowable and suspending material into the resultant products of combustion produced in said combustion chamber whereby a continuous, direct discharge of a resultant stream with

12

substantially increased velocity is produced through the said discharge nozzle against the surface to be treated.

10. The structure set forth in claim 9 wherein said last mentioned material-introducing means includes communication-orifice-area in the rear of said combustion chamber directionally disposed in a manner favorable to the flame stabilization of the combustion processes therein.

11. The structure set forth in claim 9 whereby combustion within said chamber substantially adds thermal energy to the combustible fluid media and products of combustion moving through said chamber and wherein said means for introducing readily flowable material includes a jet orifice directed generally axially and forwardly of said chamber and protruding slightly in advance of the entrance area of said combustible fluid media, whereby flame stabilization of combustion is not impaired.

12. In apparatus for producing and impacting at high velocity, a mixed stream against a surface to be treated, a longitudinal combustion chamber, a tapered reducer element communicating with the forward end of said chamber, a discharge nozzle communicating with the forward end of said reducer element, means for introducing at elevated pressure, a combustible fluid media into the rear portion of said combustion chamber, means for facilitating ignition of said medium within said chamber, said combustion adding substantial thermal energy to the materials within said chamber and substantially increasing discharge velocity from said nozzle and means for introducing readily flowable material into the stream discharged from said nozzle through aspiration action produced by said discharging stream.

13. In apparatus for producing and impacting at high velocity, a mixed stream against a surface to be treated, a longitudinal combustion chamber including a diminished discharge nozzle communicating generally axially with the forward portion of said chamber, means for introducing at elevated pressure a combustible fluid mixture into the rear portion of said chamber and entering from a generally annular rear area disposed generally concentric with the axis of said chamber, means for providing ignition of said mixture within said chamber and means for introducing readily flowable material into the products of combustion emanating from said chamber, the area of communication of said last mentioned means being disposed forwardly of said first mentioned area.

14. The structure set forth in claim 13 wherein said means for introducing readily flowable material includes a discharge element extending forwardly and generally axially within said chamber.

15. The structure set forth in claim 13 further characterized by an annular cooling duct surrounding at least a portion of said overall combustion chamber, means for communicating a cooling fluid medium to said duct adjacent one end thereof and means for communicating said duct with the interior of said overall combustion chamber, and the cooling fluid medium employed constituting one of the flowable materials previously referred to in claim 13.
